UNITED STATES PATENT OFFICE.

HAMILTON DAVIS GUFFEY, OF UNIONVILLE, MISSOURI.

COMBINED ROAD-GRADER, DRAG, AND HARROW.

No. 901,806.

Specification of Letters Patent.

Patented Oct. 20, 1908.

Application filed March 16, 1908. Serial No. 421,410

To all whom it may concern:

Be it known that I, HAMILTON DAVIS GUFFEY, a citizen of the United States, residing at Unionville, in the county of Putnam and 5 State of Missouri, have invented certain new and useful Improvements in a Combined Road-Grader, Drag, and Harrow; and I do declare the following to be a full, clear, and exact description of the invention, such as 10 will enable others skilled in the art to which it appertains to make and use the same.

This invention relates to improvements in combined road graders, drags and harrows.

The object of the invention is to provide 15 a machine of this character which may be regulated for light or heavy work and which may be quickly transformed from a road grader to a drag or harrow.

A further object of the invention is to provide 20 means whereby the draft connections may be regulated to change the position of the grader.

With these and other objects in view, the 25 invention consists of certain novel features of construction, combination and arrangement of parts as will be described and particularly pointed out in the appended claims.

In the accompanying drawings, Figure 1 30 is a top plan view of the invention arranged as a grader; Fig. 2 is a sectional view taken on the line 2—2 of Fig. 1, Fig. 3 is a sectional view on the line 3—3 of Fig. 1. Fig. 4 is a plan view of the machine arranged for 35 light work; Fig. 5 is a similar view showing the machine arranged as a harrow; and Fig. 6 is a longitudinal sectional view of the machine in the form shown in Fig. 6.

Referring more particularly to the drawings, 1 denotes the scraper blades or bars of the machine which are connected together 40 at their upper edges by a series of obliquely disposed connecting bars, 2, and are held in position by a brace bar, 3. The blades, 1, 45 consist of a vertical portion, 4, at the upper and lower edges of which are formed forwardly projecting inclined or beveled extensions, 5. The beveled sides or faces of said extensions may be, if desired, provided with 50 removable scraper plates, 6, and, if desired, similar plates, 7, may be removably secured to the rear side of the blades adjacent to their lower edges. The blades may also be provided on their lower sides and adjacent 55 to their forward edges with metal shoes or plates, 8, the forward edges of which engage

the lower edges of the front scraping plates, 6, when the latter are applied to the blades.

Secured to the forward end of the central connecting bar, 2, is a clevis, 9, with which 60 is adapted to be loosely connected by means of an eye, 10, a draft tongue, 12. The draft tongue is provided on its lower side with a guard plate, 13, between which, and the underside of the tongue, is pivotally mounted 65 a whiffletree or similar draft device, 14, said whiffletree being pivotally connected with the tongue by a pin or bolt, 15. On the opposite side of the tongue, adjacent to its rear end, are draft regulating hooks, 16, to 70 which are adjustably connected the forward ends of draft regulating chains, 17, the inner ends of which are connected to the forward ends of the outer connecting bars, 2. On the outer connecting bar, adjacent to one 75 end of the blades, is secured a driver's seat, 18.

Arranged between the ends of the blades at one side of the machine is a spacing block, 19, to the outer side of which is secured a guiding shoe, or landside, 20, the lower edge of which projects below the lower sides of the blades and is adapted to enter the ground and thereby guide or hold the machine to its work. The landside is 80 preferably removable and may be detached from the machine when desired.

In Fig. 5 of the drawings, the machine is shown as having the rear blade removed and the brace bar 3 connected at one end to 90 one end of the forward blade, and at its opposite end to the rear end of the connecting rod at the opposite side of the machine. When arranged in this position, the grader is adapted for use in connection with light 95 work. When the parts are arranged in the position shown in Fig. 5, the device may be employed as a harrow, and when so used is provided with a supplemental tooth bar, 21, which is bolted or otherwise secured to the 100 rear side of the front blade and is provided throughout its length with a series of harrow teeth which project below the forward blade in position to enter the ground. The connecting bars, 2, are preferably provided 105 with a series of apertures, 22, adapted to receive harrow teeth, 23, which are detachably secured in any suitable manner.

In the normal working position of the machine, as shown in Fig. 1, the draft regulating chains, 17, are connected loosely to the draft hooks, 16. When, however, it is

desired to change the position of the grader, or scrape more or less dirt in either direction, the chain on one side or the other of the tongue is shortened by connecting one of the rear links with the hook, while the chain on the opposite side is slackened.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim as new and desire to secure by Letters-Patent, is:

1. A combined road grader, drag and harrow comprising transversely disposed blades, a landside removably attached between the ends of the blades at one side of the grader, and means whereby the position of the grader may be changed to throw the dirt to either one side or the other.

2. In a machine of the character described, transversely disposed blades having along their upper and lower edges forwardly projecting beveled extensions, a landside adapted to be detachably secured between the ends of the blades, at one side of the machine, a loosely connected draft tongue, and detach-

able controlling devices connected to the opposite ends of the grader and to the opposite sides of said tongue whereby the position of the grader may be regulated to throw the dirt to one side or the other, substantially as described.

3. A machine of the character described, comprising transversely disposed blades, a series of connecting bars to secure said blades together, a brace bar to hold said blades in operative position, a draft hook, a tongue loosely connected to said draft hook, draft regulating chains connected to the opposite ends of the grader and to said tongue, and a landside secured to the ends of said blades along one side of the machine, substantially as described.

4. A machine of the character described comprising transversely disposed blades, a series of connecting bars, said bars having formed therein a series of harrow teeth passages, a brace bar, a landside arranged along one side of the grader, a detachable harrow bar, a draft tongue, and means to connect the machine with said tongue whereby the position of the former may be changed, substantially as described.

In testimony whereof I have hereunto set my hand in presence of two subscribing witnesses.

HAMILTON DAVIS GUFFEY.
